United States Patent Office

Des. 187,137
Patented Feb. 2, 1960

187,137

DESK OR SIMILAR MEMBER

Trace S. Christenson, Jr., South Bend, and Howard B. Barber, North Manchester, Ind., assignors to Peabody Seating Company, Inc., North Manchester, Ind., a corporation of Indiana

Application November 28, 1958, Serial No. 53,559

Term of patent 14 years

(Cl. D33—11)

Fig. 1 is a side view of a desk or similar article, showing our new design;

Fig. 2 is a rear elevational view; and

Fig. 3 is a top plan view thereof.

The dominant features of our design reside in those portions shown in full lines on the drawing.

We claim:

The ornamental design for a desk or similar article, substantially as shown and described.
